APPARATUS FOR MAKING BRIQUETTES

Anthony J. Langhammer, Detroit, Mich., assignor to Chrysler Corporation, Highland Park, Mich., a corporation of Delaware

Application October 20, 1941, Serial No. 415,714

7 Claims. (Cl. 78—0.5)

1

This invention relates to an improved apparatus and method for making briquettes from powdered metal materials.

More specifically, the invention pertains to an apparatus and method of this kind which is particularly adapted for producing briquettes of the above character which have a body portion of substantially uniform cross section and a tapered portion such as a body portion and ogive of a projectile.

One of the main objects of the invention is the provision of an apparatus and method of this kind which during compression of a charge of powdered metal particles into a briquette of pointed or conical end shape, subjects the particles of powdered metal in the pointed end and adjacent parts to substantially the same particle orientation shifting movement as that to which the powdered metal of the remaining portion of the article is subjected.

Another object of the invention is the provision of a briquetting apparatus and method of this kind which produces powdered metal briquettes of varying cross section that are substantially uniform in density throughout and which, when sintered, have uniform structural strength.

A further object of the invention is the provision of means for ejecting tapered briquettes of this kind from the dies in which they are formed by engagement with the base ends of the latter in order to safeguard the tapered or pointed ends thereof from injury.

A still further object of the invention is to control the compression to which the powdered metal charge is subjected in the tapered end forming portions of the dies as to guard against sticking or binding of the tapered end portions in the dies and consequently breaking of the briquette during separation thereof from the dies.

An illustrative embodiment of the invention is shown in the accompanying drawing, in which:

Fig. 1 is a fragmentary vertical sectional view of die forming apparatus embodying the invention illustrating the parts thereof in position to commence a briquette forming operation.

Fig. 2 is a vertical sectional view of the apparatus shown in Fig. 1 illustrating the parts thereof in the final briquette compressing stage.

Fig. 3 is a side elevational view, partly in section, of die forming apparatus embodying the invention and illustrating one form of mechanism by which the die parts may be operated.

The apparatus and method embodying the invention is adapted for use in forming articles of diverse shapes and may be employed to advantage in the forming of powdered metal briquettes which have a body portion of cylindrical or other uniform cross section and a tapered or conical end portion. For the purpose of illustrating the invention, there is shown in the drawing, the application of the apparatus and method to the

2

forming of projectiles of the type which have a cylindrical body portion and a tapered ogive. Projectile briquettes formed in accordance with the invention may be sintered in a non-oxidizing or reducing atmosphere and brought to final desired dimensions and contour in a suitable sizing operation such as that illustrated in United States Patent No. 2,226,002 issued to A. J. Langhammer on December 24, 1940. The powdered metal charge may comprise particles of a single powdered metal or a mixture of metal particles such as tin and copper.

In operating upon particles of powdered metal to bring them to compact briquette form, it is desirable to have the particles of metal at all positions in the charge undergo substantially the same amount of movement relative to the die structure or an amount of movement relative thereto of substantially the same order. This

movement of the particles relative to the die parts during compression of a charge produces a particle orientation which facilitates compression into a dense structure. If, for example, one portion of a charge is held at rest while compression is applied at one extremity of the charge, the particles of metal at the extremity of the charge upon which compression was applied shift relative to the die substantially more than the particles of metal at the extremity of the charge which was held at rest and as a result, the particles of metal which moved relative to the die underwent orientation which the particles of metal which were held at rest were not subjected to. It is found that the parts of the compressed product comprising particles which were permitted to orient themselves during compression have a substantially greater density than the portion of the resulting briquette comprising particles which were held at rest.

With the improved briquette forming apparatus and method, all the particles of the charge are shifted relative to the die during the compressing operation sufficiently uniformly to produce a briquette of substantially uniform density throughout. This is accomplished even in the formation of briquettes having body portions of substantially uniform cross section and tapered ends.

The apparatus comprises a support 10 having a bore 11 and a coaxial counterbore 12 of larger diameter than the bore 11. Slidably mounted in the bore 11 is a tubular die part 13 which has a radially extending flange 14 adapted to seat against a shoulder 15 disposed between the bore 11 and the counterbore 12. The tubular die part 13 has a cylindrical passage 16 extending therethrough which is adapted to receive a charge 17 of powdered metal. The tubular die 13 is normally urged to its upper limiting position established by abutment of the flange 14 against the shoulder 15, as viewed in Fig. 1, by a coil spring

18 which bears against the flange 14 and a shoulder 19 provided on a sleeve 20 which is threaded in the lower end portion of the counterbore 12. The upper extremity 21 of the sleeve 20 is adapted to abut the lower side of the flange 14 of the die part 13 to establish the lower limiting position of the tubular die part 13, as illustrated in Fig. 2. The sleeve 20 may be set in a selected position by tightening a set screw 22 threaded in an aperture formed in the neck portion 23 depending from the support 10. A plunger, generally designated by the numeral 24, is disposed below the support 10 in axial alignment with the passage 16 of the tubular die part 13. The ram 24 has a stem portion 25 which extends into the lower end portion of the passage 16 of the die part 13 in relatively close fitting relationship with respect to the walls thereof. The stem 25 serves to establish the depth of charge of powdered metal which is receivable in the upper end portion of passage 16 in the die 13. This stem also serves, as hereinafter more clearly set forth, to eject the charge after compression thereof.

Disposed above the support 10 in axial alignment with the bore 11 thereof is a ram 26 having a die part 27 on its lower extremity provided with a tapered closed end cavity 28. The die part 27 is adapted to engage the upper extremity of the shiftable tubular die part 13 when the ram is forced downwardly by mechanism hereinafter disclosed. The cavity 28 is registerable with the passage 16 and extremity 29 of the die part 27 surrounding the cavity 28 is preferably so formed as to produce a sealing fit with respect to the upper extremity of the die part 13.

After the upper end portion of the passage 16 has been filled with a charge of powdered metal or other powdered material, the ram 26 is forced downwardly to bring the die part 27 thereof into the upper end portion of the bore 11. During this movement of the ram, the tubular die part 13 is forced downwardly against the action of the spring 18 and the stem 25 of the plunger 24 is held at rest so as to produce relative movement between all portions of the charge 17 and the walls of the passage 16 and to displace some of the particles powdered material at the upper end of the charge 17 from the passage 16 into cavity 28. Further downward movement of the ram 26 causes the powdered charge to be compressed to a desired degree depending upon the extent to which the tubular die part 13 is urged downwardly by the die 27 of the ram 26.

After the charge 17 has been compressed to the desired extent, as illustrated in Fig. 2, the ram 26 is withdrawn and the spring 18 returns the tubular die part 13 to its upper limiting position. The stem 25 is urged upwardly to follow the upward movement of the tubular die part 13 and after the latter has reached its upper limiting position, the stem 25 is thrust upwardly relatively to the tubular die part 13 in order to eject the finished briquette from the passage 16.

The ram 26 and plunger 24 may be operated by any suitable coining press mechanism, an example of which is illustrated in Fig. 3. In this form of coining press construction, a cam member 30 is rotated by a shaft 31 to which it is fixed. The cam rotates in a bearing 32 having a bearing cap 33 on a link 34. Mounted on the lower end of the link 34 is a swivel joint 35 to which the ram 26 and die 27 are attached. The plunger 24 is operated by a cam 36 fixed to a shaft 37 which is driven at a predetermined time relationship with respect to the shaft 31. The cams 30

and 36 are so constructed and arranged as to produce the foregoing cycle of operation which includes the step of initially urging the ram 26 downwardly while the plunger 24 remains at rest during contact thereof with a constant radius portion of the cam 36. After the ram 26 has completed its full compression stroke, the cam 30 withdraws it. At the same time, the cam 36 commences to urge the plunger 24 upwardly.

10 During the operation of the foregoing briquette forming apparatus and method, substantially all portions of the particles of metal of the charge are subjected to orientation by movement with respect to the die part in which they are contained. A tapered end is formed on the briquette without a significant variation in density at the tapered and base end portions of the briquette. Even more important is the fact that the density of the briquette at the region of the junction of the tapered part formed in the die part 27 and the body part formed in the tubular die part 13 is substantially the same as that in the remaining portions of the briquette and consequently, the briquette does not tend to separate during the withdrawal stroke of the ram 36 in die 27. A tendency to form a protruding seam at the junction of the tapered and body portions of the briquette is mitigated by the movement of the particles past the plane at which the extremity 29 of the die part 27 engages the upper extremity of the tubular die 13. The resulting briquette is ejected from the tubular die part 13 by pressing upon its base end portion rather than its tapered end portion in order to avoid the application of excessively high unit pressure on the relatively pointed extremity of the briquette.

20 Although but one specific embodiment of the invention is herein shown and described, it is to be understood that various changes in the size, shape and arrangement of parts may be made without departing from the spirit of the invention.

30 What is claimed is:

1. Apparatus for briquetting articles from powdered metal including a support, a tubular die part having a passage therethrough shiftable mounted on said support, means for yieldably urging said tubular die part upwardly, a ram provided with a die part having a surface directly engageable with said tubular die part for positively shifting the latter against the action of said means and having a closed end cavity registerable with the passage of said tubular die part, a plunger member extending into the lower end portion of said tubular die part normally predetermineding the depth of charge of powdered metal receivable in the upper end portion of said passage and adapted to displace a portion of said charge from said passage into said closed end cavity during initial movement of said tubular die part relative to said plunger under the action of said ram and to compress said entire charge into a briquette during further movement of said ram.

2. Apparatus for briquetting articles from powdered metal including a support, a tubular die part having a passage therethrough shiftable mounted on said support, resilient means coacting between said support and said tubular die part and yieldably urging the latter upwardly, a ram provided with a die part having a surface directly engageable with said tubular die part for positively shifting it against the action of said means and having a closed end cavity registerable with the passage of the latter, a plunger

er member extending into the lower end portion of said tubular die part normally predetermining the depth of charge of powdered metal receivable in the upper end portion of said passage and adapted to displace a portion of said charge from said passage into said closed end cavity during initial movement of said tubular die part relative to said plunger under the action of said ram and to compress said entire charge into a briquette during further movement of said ram, said plunger member being shiftable relative to said support and tubular die part after withdrawal of said ram for ejecting the resulting briquette from said tubular die part.

3. Apparatus for briquetting from powdered metal articles having a portion of uniform cross section and a portion varying in cross section at successive increments of its length including a support, a tubular die part having a passage therethrough comprising an upper section of uniform cross section, means for yieldingly urging said tubular die part outwardly with respect to said support, a ram provided with a die part having a surface directly engageable with said tubular die part for positively shifting the latter against the action of said means during the initial effective portion of the stroke of said ram and having a closed end cavity registerable with the passage of said tubular die part and varying in cross section at successive increments of its length in conformity with the variation of the second mentioned portion of said article, a plunger member extending into the lower end portion of said tubular die part normally predetermining the depth of charge of powdered metal receivable in the upper end portion of said passage and adapted to displace a portion of said charge from said passage into said closed end cavity during initial movement of said tubular die part relative to said plunger under the action of said ram and to compress said entire charge into a briquette during further movement of said ram.

4. Apparatus for briquetting from powdered metal articles having a portion of uniform cross section and a portion of tapering shape including a support, a tubular die part having a passage therethrough comprising an upper section of uniform cross section, means for yieldingly urging said tubular die part outwardly with respect to said support, a ram having a die part engageable with the outer extremity of said tubular die part for positively shifting said tubular die part against the action of said means and provided with a tapered closed end cavity registerable with the passage of the latter, a plunger member extending into the lower end portion of said tubular die part normally predetermining the depth of charge of powdered metal receivable in the upper end portion of said passage and adapted to displace a portion of said charge from said passage into said closed end cavity during initial movement of said tubular die part relative to said plunger under the action of said ram and to compress said entire charge into a briquette during further relative movement of said ram and plunger, said plunger member being shiftable relative to said tubular die part for ejecting said briquette by engagement with the end thereof opposite from its tapered extremity after compression of said charge.

5. Apparatus for briquetting articles from powdered metal including a support, a tubular die part having a passage therethrough shiftably mounted on said support, spaced stops for predetermining the limits of shifting movement

of said tubular die part, means for yieldably urging said tubular die part toward one of its limiting positions, a ram for shifting said tubular die part against the action of said resilient means, said ram having a die part provided with an extremity for seating against the outer extremity of said tubular die part and having a closed end cavity registerable with the passage of the latter, a plunger member extending into the end portion of said tubular die part adjacent the opposite extremity thereof, said plunger having a close fitting relationship with respect to the walls of said passage and being adapted to predetermine the depth of charge of powdered metal receivable in the portion of said passage unoccupied by it, means for forcing said ram against said tubular die part in order to shift the latter relative to said plunger member in one direction so as to initially displace a portion of said charge from said passage into said closed end cavity of the die part of said ram and to subsequently compress said charge to a predetermined density, and means for shifting said plunger in the opposite direction relative to said tubular member for ejecting the resulting compressed charge therefrom.

6. Apparatus for forming from powdered metal a projectile shaped briquette having a cylindrical body portion and a tapered ogive including a support, a tubular die part axially shiftably mounted on said support having a passage for receiving a powdered metal charge and which is adapted to form the body portion of said briquette, a shiftable ram having a die part directly engageable with said tubular die part for positively shifting the latter independently of said powdered metal charge and provided with a tapered closed end cavity registerable with said passage for forming the ogive, mechanism for forcing said ram against said tubular die part to shift the latter axially, and means extending into the passage of said tubular die part for holding said charge against movement with the latter in order to initially displace a portion of said charge from said passage into said cavity and to thereafter compress said charge to a predetermined density during movement of said tubular die part by said ram.

7. Apparatus for forming from powdered metal a projectile shaped briquette having a cylindrical body portion and a tapered ogive including a support, a tubular die part axially shiftably mounted on said support having a passage for receiving a powdered metal charge and which is adapted to form the body portion of said briquette, a shiftable ram having a die part engageable with an extremity of said tubular die part for positively shifting the latter and provided with a tapered closed end cavity registerable with said passage for forming the ogive, mechanism for forcing said ram against said tubular die part to shift the latter axially, a shiftable plunger extending into the end of said passage opposite from said ram for holding said charge against movement with the latter in order to initially displace a portion of said charge from said passage into said cavity and to thereafter compress said charge to a predetermined density during movement of said tubular die part by said ram, and mechanism for holding said plunger at rest during said movement of said tubular die part and adapted to shift said plunger relative to the latter after compression of said charge for ejecting the latter.
